CLAIM

The ornamental design for the hose coupling with ferrule, as shown and described.

DESCRIPTION

FIG. 1 is a front, top, right-side perspective view of the hose coupling with ferrule of the present invention;

FIG. 2 is a back, bottom, left-side perspective view of the hose coupling with ferrule of the present invention;

FIG. 3 is a front view of the hose coupling with ferrule of the present invention;

FIG. 4 is a back view of the hose coupling with ferrule of the present invention;

FIG. 5 is a right-side view of the hose coupling with ferrule of the present invention;

FIG. 6 is a left-side view of the hose coupling with ferrule of the present invention;

FIG. 7 is a top view of the hose coupling with ferrule of the present invention;

FIG. 8 is a bottom view of the hose coupling with ferrule of the present invention; and,

FIG. 9 is a top, front perspective view of the hose coupling with ferrule of the present invention and showing environment including a hose sleeve in broken lines.

The drawings show a hose coupling with ferrule. The broken lines shown in the drawings encompass features of a hose coupling and hose sleeve to which the hose coupling with ferrule is attached and which form no part of the claimed design.

1 Claim, 8 Drawing Sheets
